G. A. BERG

BOTTLE WASHING MACHINE

Filed June 13, 1921

Fig. 3

INVENTOR.
Gustaf A. Berg,
BY Alfred H. Daehler,
ATTORNEY.

UNITED STATES PATENT OFFICE.

GUSTAF A. BERG, OF LOS ANGELES, CALIFORNIA.

BOTTLE-WASHING MACHINE.

Application filed June 13, 1921. Serial No. 477,088.

To all whom it may concern:

Be it known that I, GUSTAF A. BERG, a citizen of the United States, residing at Los Angeles, in the county of Los Angeles and State of California, have invented new and useful Improvements in Bottle-Washing Machines, of which the following is a specification.

This invention relates to bottle washing machines and more particularly to machines of the general character stated in which rotatable brushes are employed for the internal and external cleaning of bottles such as milk bottles and the like. The invention 10 has for its object to provide a motor driven washing machine in which provision is made for the positive and accurate mounting and driving of brush-carrying spindles and which will be relatively simple and inexpensive in construction and organization 15 taken in connection with high efficiency and general superiority in service.

Bottle washing machines of this general character as ordinarily constructed have the 20 disadvantage of imperfect driving and mounting means for the spindles thereof, lack of portability, and many other disadvantages such as frequent breakage of bottles when the brushes loosen in their 25 chucks due to wear, and the like. A very frequent cause of trouble is in belt slippage, as in use the washing water employed 30 splashes over the drive means and acts as a lubricant so retarding and interfering 35 with the bottle washing operation.

In accordance with the invention, and in the preferred practice thereof, I provide a base in which a plurality of hollow rotatable double-ended spindles are mounted, a superposed electric motor, and means of positive 40 drive between the motor and all of the spindles. Furthermore, a water-proof gear casing or housing is formed in connection with or mounted upon the base and the 45 entire resulting portable unit otherwise rendered waterproof.

With the above and other objects in view, the invention consists in the novel and useful provision, formation, combination, association and relative arrangement of parts, members and features, all as hereinafter described, shown in the drawing, and finally pointed out in claims.

In the drawing:

55 Figure 1 is a fragmentary longitudinal sectional view, parts being shown in eleva-

tion, of a bottle washing machine constructed, organized and used in accordance with the invention;

Figure 2 is a fragmentary end view, with 60 parts in section, taken on the line X^2-X^2 , Figure 1;

Figure 3 is a fragmentary plan view of parts of the bottle washing machine illustrating the manner in which bottles may be 65 simultaneously internally and externally cleansed;

Figure 4 is a longitudinal vertical sectional view of one of the spindle chucks, a brush handle being fragmentarily shown as 70 securely held therein;

Figure 5 is a fragmentary transverse partially sectional detail view showing improved spindle lubrication features of the 75 machine; and

Figure 6 is a fragmentary detail view of lubrication features.

Corresponding parts in all the figures are designated by like reference characters.

Referring with particularity to the drawing, in the embodiment of the invention therein shown, A designates the base of my improved bottle washing machine, B designates a hollow extension of said base forming an enclosing housing or casing for the 80 positive driving means, C designates such driving means, D designates, in each instance a brush-carrying spindle rotatably mounted in the base A, and E designates an electric motor of the enclosed type superposed upon the base A and suitably and 85 closely connected with all of the spindles D through the positive drive means C.

The base A is shown as preferably comprising a casting 7 having apertured lugs or 90 ears 8 by means of which the portable washer may be secured in juxtaposition to a washing trough, not shown, and as having upstanding apertured motor-base receiving lugs 9 to which the base 10 of the 100 motor is secured by means of suitable screws 11 passed through apertured feet 12 formed on such motor base 10, so to rigidly unite the motor E and the base A. At the driving end of the motor shaft, the base is 105 formed with a preferably integral vertical transverse wall 13, which wall 13 together with a hollow box-like cover 14 applied thereto, forms the gear housing or upwardly extending base extension in which the drive 110 means C are disposed. The base A is preferably provided with spindle-receiving aper-

tures 15. In the preferred construction, three horizontal bosses 16 are formed on the base A at each end thereof and the spindle-receiving apertures 15 extend through such bosses 16, so providing a pair of spaced 5 bearings for each spindle D.

The positive driving means C is shown as comprising an enclosed reduction gearing mechanism or means which is shown as a 10 pinion 17 secured to the shaft of the motor and disposed in the extension B, the wall 13 being apertured, as at 13^a, to accommodate the projecting end of the motor-spindle. Rotatably mounted in or upon the wall 13 15 and in mesh with pinion 17 is an idler or intermediate driving gear 18 which is in mesh with a gear 19 fixed to the intermediate spindle D. Each of the other spindles D is provided with a gear 20 which meshes 20 with the gear 19 at the respective side thereof. After all the gears and the pinion are assembled, the cover 14 may be secured to the plate or wall 13 and suitably packed thereagainst to render the gear casing liquid 25 proof so to insure the retention of lubricant therein as well as to exclude water or moisture. The cover 14 is provided with a series of apertures 14^a, one to accommodate the respective projecting end of each spindle D.

The spindles D each comprise a tube 21 having a bore 21^a extending from end to end thereof, and are mounted for rotation one in each of the sets of journals provided on the 35 base and preferably each has both its ends projecting from the base to receive a chuck. Each such chuck preferably comprises a tubular body portion 22 having a bore 22^a extending from end to end thereof and such bore 22^a is preferably enlarged and formed 40 with an internal tapering thread as at 22^b. Each spindle end has a corresponding external tapering thread 23 to permit of the mounting thereon of the corresponding chuck 45 in rigid relation. At its outer end, each chuck is slotted as at 24 and externally provided with a tapering thread 24^a to which a nut portion 25 provided with an internal tapering thread 25^a and a brush-shank 50 receiving orifice is fitted. It is to be noted that by this construction I eliminate all possibility of chuck or brush oscillation or gyration which is a very objectionable feature of machines of this general nature as 55 ordinarily constructed. It is only necessary to tighten up the tapering threaded joints to insure true coaxial spinning of each chuck with its spindle and the brush handle secured thereby.

60 The spindles in certain embodiments of the invention being double-ended, such machine may be used by two washers or operators at the same time. In each such double-ended spindle, the brush handles, 65 which are preferably cylindrical, may be

abutted in the spindle and the chucks tightened, whereupon a perfectly smooth running device is had.

The motor E may comprise an electric motor of any preferred or standard voltage 70 and power, all in accordance with the requirements of any given case.

An outwardly flaring splash plate 26 may be provided at each end of the machine, suitable spindle apertures 26^a being provided 75 therein. A casing 27 may extend from one such plate 26 to the other to provide for the further waterproofing of the machine. The conducting cord or wires e leading to the motor may extend through a 80 suitable aperture in the casing 27 and be provided outwardly thereof with an attachment plug, all as will be well understood by those skilled in the art to which this invention appertains.

85 A novel lubricating device is shown at each set of journal bearings and each such device may comprise a tube 28 apertured at each journal bearing as at 28^a to receive a lubricant feeding nipple 29, one of which is 90 tapped into each journal bearing. At each end of the tube 28 a lubricant feeding cup 30 is provided, so producing a double feeding device for the spindle lubricant.

The spindles are shown as disposed in 95 a common horizontal plane in the base, so providing for the washing of bottles as illustrated in plan in Figure 3, the intermediate brush d washing the exterior of the two bottles shown, while each of the outer 100 brushes d' washes the interior of one of the bottles.

Having thus disclosed my invention, I claim and desire to secure by Letters Patent:—

105 1. In a portable waterproof unitary structure of the character disclosed, a supporting base having a vertically ranging hollow extension forming a gear casing, and an electric motor of the enclosed type united 110 with said base and having a driving shaft penetrating the inclosed casing, spindles rotatably journaled in said base and extending therefrom at opposite ends, said spindles 115 penetrating the said casing, brushes supported by said spindles, and spindle-driving means inclosed within said casing and including reduction gearing between the said spindles and the said motor shaft.

120 2. In a portable waterproof unitary structure of the character disclosed, a supporting base having a vertically ranging hollow extension forming a gear casing, an electric motor of the enclosed type united with said base and having a driving pinion on its 125 shaft and disposed in said casing, three rotatable spindles in said base and projecting therefrom at both ends, brushes supported by said spindles, a gear on each spindle shaft, and an idler gear in mesh with 130

said motor shaft pinion and one of said first named gears; each of said spindles having a bore, a tapered threaded end, a hollow chuck element having internal 5 threads engaged with said tapered threaded ends, and a chucking collar having tapered threaded engagement with said element.

3. A bottle washing machine having a supporting base, a motor mounted thereon, 10 a hood engaged over the base and presenting splash-plates at opposite ends thereof, said hood inclosing the said motor, spindles penetrating the said plates, driving means between the motor and the inclosed portions 15 of the said spindles, and a washer element at the outer end of each spindle.

4. A bottle washing machine having a supporting base presenting a vertical gear casing, an electric motor secured to the said 20 base rearwardly of the said casing, a hood engaged over the said base and inclosing the said motor and gear casing, said hood presenting a splash plate forwardly of the

said casing, a spindle penetrating the said splash plate and the casing, a brush at the 25 outer end of the said spindle, and driving means between the said motor and the said spindle, said driving means being inclosed within the said casing.

5. A bottle washing machine comprising 30 a base, upright splash plates at opposite edges of the base, a motor mounted on the base, a hood fitting over the base between the splash plates and co-acting with the latter to provide a motor-inclosing casing, and 35 revoluble spindles driven from the motor and projecting outwardly through the splash plates and presenting brush-holding means forwardly of the plates.

In testimony whereof, I have signed my 40 name to this specification in the presence of two subscribing witnesses.

GUSTAF A. BERG.
